UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

REVERSIBLE HEAD-FREE RAIL JOINT.

Application filed June 30, 1927. Serial No. 202,684.

This invention relates to an improvement in the head-free type of rail joint wherein the joint bar has an anchorage and loading engagement in the head fillet of the rail and 5 adjustable bearing engagement on the upper side of the rail flange.

In the head-free type of rail joint the distinctive structural characteristic thereof is to provide for an anchorage that gives 10 the head of the bar clearance from the underside of the rail head and a loading engagement at the head fillet of the rail, such a relation of the joint bar to the rail providing an effective way to assimilate loading 15 and deflection forces to which a rail joint is subjected, and to bring the head of the bar to solid resistance to load deflections.

Because of the special distribution of metal required in a head-free joint bar to 20 establish the proper metal ratios whereby it most effectively will resist the loading and deflecting forces which concentrate at the head fillet of the rail it has been found difficult to adapt this type of joint bar to switch 25 and frog locations. Also, heretofore no special provision has been made in the head-free type of joint bar to continue its use when such wear in the joint has occurred that the "take up" or adjustment has been ex- 30 hausted. Accordingly, it is the purpose of the present invention to provide a modified form of head-free joint bar that will meet both of these conditions, that is, a head-free joint bar that can be used in frog and switch 35 locations in the track and which also may be reversed when further adjustment is im- possible, thereby greatly increasing the life of the joint, while at the same time main- taining its head-free characteristic at all 40 times.

With these and other objects in view which will readily appear to those familiar with the art, the invention consists in the novel structural shape herein illustrated, 45 described and claimed and to illustrate the susceptibility of the invention to modification certain preferred embodiments are illus- trated in the accompanying drawings, in which:—

50 Figure 1 is a sectional view of a head-free type of joint bar, of a reversible construction and having a symmetrical formation respectively above and below the middle line or axis thereof.

55 Figure 2 is a similar view showing the

invention embodied in a joint bar shape having an unsymmetrical construction, and not truly balanced as to its metal ratios.

The novel reversible head-free joint bar includes in its construction three principal elements, namely, a relatively thin vertical web 1, an upper laterally enlarged head portion 2, and a lower laterally enlarged foot portion 3. Considering the joint bar from the aspect of its initial application before 60 undue wear or material adjustment have occurred it will be observed that the upper laterally enlarged head portion 2 thereof is provided with an inner rounded bearing bulb or ball 4 whose curved bearing surface 70 5 is adapted to have an anchorage and bearing engagement in the arcuate bearing seat 6 provided by the curved head fillet 7 of the rail R. In this construction the top surface 8 of the joint bar has a clearance 75 or is free from at least the major portion of the fishing surface 9 at the underside of the rail head. In these particulars the joint bar is the head-free type of bar disclosed in the reissue patent of Thomson 80 No. 15,773 granted February 19, 1924 and the lower foot portion 3 of the bar has an inner and upper adjustment on the upper side of the rail base flange as wear occurs, thereby rocking or oscillating the bar in- 85 ward with the coacting bearing surfaces 5 and 6 acting as a fulcrum. This mounting and adjustment practically eliminates wear on the joint bar at its head fillet engagement of the rail, but continued adjustment and 90 use produces wear to some extent on the part 8^a that engages the upper side of the rail base flange, which wear, in conjunction with the wear which occurs in and on the upper side of the rail base flange, contribute, 95 to the eventual exhaustion of the "take up" or adjustment for the bar.

Accordingly, to meet the condition just referred to, the present invention provides a novel formation for the lower foot portion 100 3 of the joint bar. This formation is in effect an enlarged bulb of metal at the bottom of the bar, which bulb includes an outer rounded bearing ball 4^a, an inner enlarged heel projection 10 and a rail flange engag- 105 ing surface 8^a. In the embodiment of the invention shown in Fig. 1 the said lower laterally enlarged foot portion 3 having the structural elements referred to is intended to be a duplicate in shape, area and metal 110

ratio distribution to the upper laterally enlarged head portion 2, and thereby in balanced relation, thus giving an ideal construction. At the same time the outer 5 rounded bearing ball 4^a of the foot portion having the same radius and other general contour as the inner rounded bearing ball 4 when the rail flange engaging surface 8^a and the rail base flange become unduly 10 worn so that no further "take up" is available in the bar, the same is reversed, thereby to bring the lower foot portion 3 uppermost so as to become the head of the bar, and the rounded bearing ball 4^a thereof into anchorage 15 and bearing engagement with the bearing seat 6 of the head fillet 7. This also has the effect of bringing a fresh unworn surface 8 over the rail base flange, thus restoring the adjustment or "take up" for 20 the bar while not in the least interfering with its true functioning as a head-free joint bar.

It also will be observed that the lower laterally enlarged foot portion 3 is substantially 25 within the plane of the outer edge of the rail base flange so as not to interfere with the use of the bar in frog and switch locations in track.

By way of illustrating the range of modification that may be resorted to in carrying forward the invention there is shown in Fig. 2 of the drawings the reversible head-free joint bar designed in unsymmetrical shape so that the head and foot portions 2 and 3 thereof are not of duplicate area, contour and metal ratio distribution, but are alike with respect to having the inner rounded bearing ball 4 of the head portion 2 with a similar radius and contour to the outer 40 rounded bearing ball 4^a of the foot portion so that either the ball 4 or the ball 4^a may be seated in the bearing seat of the head fillet of the rail to carry out the head-free functions of the bar regardless of whether 45 the head or foot portions thereof are uppermost. In other respects as to the detail elements thereof the modified form of bar shown in Fig. 2 is the same as the bar previously described and illustrated in Fig. 1 50 of the drawings.

From the foregoing it is thought that the

structural features and special advantages of the invention will be understood by those familiar with the subject without further description and it will of course be understood that changes in the form, proportion and minor details of construction may be resorted to without departing from the spirit or sacrificing any of the advantages of the invention. 60

I claim:

1. A reversible head-free rail joint bar including a web provided respectively with upper and lower laterally enlarged head and foot portions, each having a rounded bearing ball adapted to have an anchorage and bearing engagement in the head fillet of the rail. 65

2. A reversible head-free joint bar including a web provided respectively with upper and lower laterally enlarged head and foot portions, each having a rounded bearing ball adapted to have an anchorage and bearing engagement with the rail head fillet and each having a rail flange engaging 75 surface adapted to engage the upper side of the rail base flange. 70

3. A reversible head-free joint bar including a web provided respectively with upper and lower laterally enlarged head and foot 80 portions, each having inner and outer projections and a surface between these projections which is adapted to engage the upper side of the rail base flange, one of the projections of the head and foot portions of the bar being of rounded formation and adapted to have an anchorage and bearing engagement with the rail head fillet. 85

4. A head-free rail joint structure including in combination with the rail, a reversible joint bar provided with laterally enlarged head and foot portions, each having a rounded bearing ball for anchorage in the rail head fillet and a rail flange engaging surface, the laterally enlarged foot portion of the bar being in the form of a metal bulb lying substantially inside of the plane of the outer edge of the rail flange. 95

In testimony whereof I hereunto affix my signature.

VICTOR C. ARMSTRONG
